Radio Corporation of America, a corporation of
Delaware

Application July 30, 1942, Serial No. 452,871

20 Claims. (Cl. 178—69.5)

This invention relates to an improvement in facsimile receivers and more particularly to a system for maintaining a facsimile receiving apparatus in synchronous operation with the operation of the facsimile transmitter.

At the facsimile transmitting apparatus the copy to be transmitted is positioned in a machine or transmitter such that the copy can be scanned in a line-by-line fashion to produce facsimile signals. These signals are then transmitted to the receiver by any appropriate means and are then utilized to produce a facsimile of the original copy. Naturally, it is necessary to maintain synchronous operation between the transmitter and the one or more receivers in order that a true copy of the original may be produced. For this purpose it is generally customary to transmit a synchronizing or framing signal at the end of each line scanned at the transmitter, this signal being generally transmitted to the receivers by the same method utilized for the transmission of facsimile signals. This synchronizing or framing impulse is then utilized at the receiver for maintaining the receiver in synchronous operation with the transmitter.

Various methods have been devised for maintaining synchronous operation between the facsimile receiver and the transmitter. However, many of the prior art systems are not fully adequate and do not produce the required degree of synchronous operation especially where high speed facsimile is used. Furthermore, in other known synchronizing systems, the reception of a synchronizing or framing signal is necessary to maintain proper operation of the receiver with the result that the absence of one or more synchronizing or framing impulses in succession may often cause the facsimile receiver to drop completely out of synchronism with the transmitter. The absence of one or more synchronizing or framing impulses may frequently occur for various reasons such as, for example, fading or a momentary inoperative condition of a part of the system. Various other known facsimile synchronizing systems have the objection that, in the absence of a synchronizing or framing signal, the receiver may immediately begin to run too fast or too slow and cause a distortion in the produced copy. Furthermore, in other known synchronizing systems the synchronizing or framing impulse is effective to control the speed of operation of the facsimile receiver only during the intervals that the synchronizing signal is being received, the machine or receiver running "free" between synchronizing intervals.

Such systems may cause distortion of the produced copy particularly in the region at the end of each scanned line.

In the present facsimile synchronizing system 5 all of the above referred to objections have been overcome and through the use of the present invention it is possible to maintain very accurate synchronism between a facsimile receiver and transmitter even under conditions of fading 10 or momentary absence of the synchronizing or framing impulses. Furthermore, through the use of the present invention it is possible to produce and maintain a correction voltage for adjusting the speed of operation of the facsimile receiver 15 until the operating speed has been adjusted to bring the operation of the receiver in synchronism with the transmitter.

The present invention utilizes a Wheatstone bridge arrangement with means responsive to 20 received framing impulses for producing a speed correcting voltage, the magnitude of the produced voltage, as well as its polarity, representing the error in lack of synchronism and whether or not the receiver is operating fast or slow. When 25 the facsimile receiver is in synchronism with the transmitter no correcting voltage is produced, but when the receiver is operating slow with respect to the transmitter a correcting voltage of one polarity is produced, with the magnitude of 30 the voltage being a function of the lack of synchronism, whereas when the receiver is operating fast a voltage of the opposite polarity is produced in a magnitude which is also a function of the degree of lack of synchronism.

35 The present invention also includes means for producing a "second order" correction and adding such correction voltage to the original correction voltage thereby improving the operation of the facsimile receiver. Theoretically, complete 40 and absolute correction for maintaining absolute synchronism between transmitter and receiver would only be possible by using an infinite series of corrections. However, it has been found that the use of the first and second order correction 45 of the series is sufficient to maintain wholly adequate synchronous operation.

First order correction is a condition in which 50 the correction voltage is produced at each synchronizing or framing interval, the circuit arrangement being such that the correction voltage entirely disappears before (preferably just before) the next synchronizing or framing interval arrives. If the receiver is still out of synchronism a new correction voltage is produced commensurate with the then lack of synchronism. Such a

system will operate to maintain synchronous operation, but in cases where higher accuracy of phasing and better synchronism are desired the use of the first order correction voltage is insufficient.

In second order correction a certain predetermined amount of the produced correction voltage still persists at the end of a particular line, this voltage being readjusted by the new synchronizing impulse in accordance with the lack of synchronism at that time and the new voltage is then used to correct for the lack of synchronism, this voltage or a portion thereof being maintained throughout the entire scanned line. A certain predetermined voltage may, therefore, be maintained to assure synchronous operation of the receiver and the system is, therefore, asymptotic to synchronous speed.

It is, therefore, one purpose of the present invention to provide a new and improved synchronizing system for use in a facsimile receiver whereby the receiver may be maintained in accurate synchronism with the transmitter.

Another purpose of the present invention resides in the provision of a circuit arrangement whereby a correction voltage is developed at the facsimile receiver, the correction voltage being suitable for assuring or maintaining synchronous operation of the receiver with the transmitter.

Still another purpose of the present invention resides in the provision of means for producing a correction voltage being determined in accordance with whether the receiver is operating fast or slow with respect to the transmitter.

A still further purpose of the present invention resides in the provision of means at a facsimile receiver responsive to synchronizing or framing impulses for producing a correction voltage, the intensity of the correction voltage being determined in accordance with the lack of synchronism between the facsimile receiver and the transmitter.

Another purpose of the present invention resides in the provision of means whereby the produced correction voltage, or a portion thereof, may be maintained throughout each succeeding scanned line in order to assure more accurate synchronism between the receiver and transmitter.

A still further purpose of the present invention resides in the provision of means for producing both first and second order correction voltages for maintaining synchronous operation between the receiver and the transmitter.

Various other purposes and advantages of the present invention will become more apparent to those skilled in the art from the following detailed description and claims, particularly when considered in conjunction with the drawings, wherein

Figure 1 represents schematically one form of the present invention; and

Figure 2 shows a plurality of curves representing produced correction voltages under various conditions of phase and synchronism.

Referring now to Figure 1, there is shown a bridge network which operates to compare the phase of received synchronizing or framing signals to the phase of operation of the local recorder or receiver to thereby produce a positive or negative voltage output which represents in polarity and amplitude the error found to be present. This produced voltage may then be used to bring about or produce the desired synchronous operation of the receiver.

The system shown in Figure 1 responds to short synchronizing or framing impulses received from the transmitter, generally in the form of short tone signals which are transmitted at the start of each scanned line. Actually the synchronizing or framing signals may be sent more frequently than for each line if more accurate synchronizing is desired.

The system includes input transformer 10 having input terminals 12 connected to the primary thereof. A wave form, such as shown at 14, is to be applied to the terminals 12, and as shown in Figure 1, the wave form 14 comprises a series of short tone signals identical to or corresponding to the synchronizing signals transmitted by the facsimile transmitter.

A full wave rectifier tube 16 is provided having a cathode and a pair of anodes. The ends of the secondary winding of the transformer 10 are connected to the anodes of the full wave rectifier tube so that when a synchronizing tone signal is received and applied to the rectifier tube 16 a voltage will be developed across the load resistance 18 and the condenser 20 connected in parallel therewith. The produced voltage impulses are then applied to a discharge tube 22 having a cathode, a control electrode and an anode. The potentials are naturally applied between cathode and control electrode, and since the cathode of the rectifier 16 and the cathode of the tube 22 are connected together, synchronizing or framing impulses produce a negative voltage impulse upon the control electrode of tube 22. While this voltage is sufficiently negative to bias tube 22 to cause plate current cut-off, it will, however, be apparent that in the absence of a negative impulse or framing signal the tube 22 draws a certain amount of plate current. Tube 22 conditions the bridge for operation to indicate phase displacement and to thereby produce a correction voltage so that when no negative impulse is applied to the grid of tube 22 (as, for example, under abnormal conditions) the bridge is rendered inoperative and no correction voltage is produced.

The four arms of the Wheatstone bridge are represented by tubes 24 and 26 and resistances 28 and 30. Each of the tubes 24 and 26 include a cathode, a control electrode and an anode. The tubes 24 and 26 are connected in series with the anode of tube 24 connected to the cathode of tube 26.

A source of potential (not shown) is provided, the positive terminal of the source of potential being connected to terminal 32, while the negative terminal of the source of potential is connected to terminal 34. Between terminals 32 and 34 are serially connected resistances 28 and 30, as well as an additional resistance 36. The cathode of tube 24 is connected to the junction of resistances 28 and 36 by way of adjustable resistance 38, while the anode of tube 26 is connected to the positive terminal 32 by resistance 40, which may be made adjustable if desired. There is included in this connection the facsimile receiver commutator which affords a means of comparison between the phase of operation of the receiver and the received synchronizing or framing impulses. The facsimile receiver printer drum is shown generally at 42 and in normal operation one line of the facsimile copy is produced for each revolution of the drum (when a single helix is used) by cooperation of the helix with the usual printer bar, (not shown) but illustrated in relation to the helix for instance by 70 75 Reissue Patent No. 20,152, dated October 27, 1936,

granted to Charles J. Young. The printer drum 42 carries a conducting segment 44 which extends preferably 180 degrees around the drum and a cooperating brush contact 46 is arranged to cooperate with the conducting segment. The conducting segment 44 and the brush 46 constitute the commutator for opening and closing the circuit between the anode 26 of the positive terminal 32. Through the operation of the commutator the circuit is, therefore, closed during one-half revolution of the printer drum and is open during the remaining half revolution of the drum.

The circuit also includes a diode 48 having a cathode and an anode. The cathode is connected to the control electrode of tube 26 by grid bias resistor 50 and to the junction of resistances 38 and 28 by a time constant circuit including parallel resistance 52 and condenser 54. The anode of tube 48 is connected to the positive terminal 32 by resistance 56 and the anode of this tube is also connected to the anode of tube 22 by resistance 58. The anode of tube 22 is connected to the control electrode of tube 44 by the grid bias resistor 60.

The output voltage developed by the bridge is, therefore, available from the junction of resistances 28 and 30 and from the conductor connecting the anode of tube 24 to the cathode of tube 26. A condenser 62 is connected between these points and the condenser 62 has connected in parallel therewith a series combination including resistance 64 and condenser 66. The resistance 64 is actually the resistance element of a potentiometer including movable contact 68. The output terminals for the control circuit are indicated at 70 and 72, the former being connected to the adjustable contact 68 and the latter being connected to the junction of the resistances 28 and 30.

For preferred operation of the system it is necessary that the bridge be balanced so that when both tubes 24 and 26 are conducting and are drawing maximum permissible plate current (with the commutator closed) no voltage will be developed across the condenser 62. This balanced condition may be brought about by an adjustment of resistance 38 (or by an adjustment of resistance 40, or both). Once the bridge has been adjusted further adjustment is generally not necessary until one or the other, or both, of the tubes 24 and 26 are replaced. Aging of the tubes may, however, necessitate an occasional readjustment of the bridge.

The operation of the system will now be described. Tube 24 is held at cut-off by the conducting condition of tube 22 when no input or framing signal is present. When a framing signal is received, however, and a negative potential is simultaneously applied to the control electrode of the tube 22, the potential of the anode of tube 22 increases in a positive direction and thereby permits current to be drawn by tube 24. Tube 26 is normally held non-conducting by application of a negative potential to the control electrode of this tube through resistances 50 and 52. When neither of the tubes are conducting, naturally the condenser 62 is electrically isolated from the system and receives no charging voltage. This condition exists irrespective of the position of the commutator 44-46, since if the control electrode of both of tubes 24 and 26 have applied thereto negative potentials sufficient to block the tubes, condenser 62 cannot receive a charging

voltage, and the position of the commutator is immaterial.

If the facsimile receiver is operating at proper speed and is in frame (proper phase) with the transmitter the commutator 44-46 closes the circuit to the anode of tube 26 prior to the time when the framing or synchronizing signal is received. The synchronizing or framing signal then conditions the bridge for operation by rendering tube 22 non-conducting and accordingly tube 24 conducting. The increased positive potential on the anode of tube 48 (due to non-conducting condition of tube 22) then permits this tube to draw current through resistance 52 and condenser 54 thereby charging condenser 54 up to the potential across resistances 28 and 30. The control electrode of tube 26 is then raised to a zero potential with respect to its cathode by reason of the operation of tube 48 and the charge potential on condenser 54. Both of tubes 24 and 26 are, therefore, rendered conductive simultaneously and if the bridge is properly adjusted as above described, no potential charge is deposited on condenser 62, and accordingly, no potential is available at the output terminals 70-72. Neither of the control electrodes of tubes 24 and 26 can be raised to a potential above the potential of their cathodes due to the biasing effect of grid current in resistances 60 and 58, respectively. Inasmuch as the potential of the control electrode of tubes 24 and 26 is fixed when the tubes are conducting the amount of current passed by each of the tubes under conducting conditions remains constant and a properly balanced condition of the bridge can be maintained, once it is established.

At the termination of the framing or synchronizing signal tube 22 will again be permitted to draw current with the result that tube 24 is immediately biased to cut-off. Under conditions of exact proper phase relationship between the receiver and the transmitter the commutator switch 44-46 will open the anode circuit of tube 26 exactly at the same instant that tube 24 is rendered non-conducting. Both of the tubes 24 and 26, therefore, are rendered non-conducting exactly simultaneously when the receiver is in exact synchronism and in proper phase with the transmitter. Under this condition no voltage is produced on condenser 62 since, as described above, both of tubes 24 and 26 are rendered conducting and non-conducting exactly simultaneously.

For further explaining the operation of the system, reference is now made to Figure 2 where-in a series of curves are shown. The curves are drawn in relation to time, and the interval from T_1 to T_3 corresponds to one synchronizing or framing interval which in this instance represents one line interval. Furthermore, when a single spiral helix is used this lapse of time from T_1 to T_3 also corresponds to the time required for one revolution of the facsimile receiver printer drum. At the top of the figure is indicated the interval at which the commutator contacts open which is marked T_2 . The contacts close at the interval marked T_3 which corresponds, of course, to the beginning of a new interval T_1 .

Under conditions when the facsimile receiver is operating in proper phase and synchronism with the transmitter the synchronizing impulse, as represented by curve 15 in Figure 2, shows the relation of the synchronizing impulse to the operation of the commutator contacts 44-46.

Immediately below curve 78 are curves 76 and 77 which represent, respectively, the current through tubes 28 and 24. It will be noticed that tubes 24 and 28 begin to pass current at the same instant and are both blocked or rendered non-conductive at the same instant, this latter instant corresponding to the time when the commutator contacts open at T_2 . As explained above, under these conditions no charge will be placed on condenser 62 and the dotted line shown at 78 indicates a zero charge condition for the condenser 62.

If the recorder or receiver is operating slow with respect to the transmitter a correction voltage will then be developed on condenser 62. Under such a condition it will be assumed that the curve 79 in Figure 2 represents the received synchronizing impulse, and its relation to time T_2 . As soon as the synchronizing impulse arrives or is received (with the commutator contacts closed) both tubes 24 and 28 are rendered conductive as explained above. Both tubes continue to conduct until the termination of the received synchronizing signal when tube 22 is rendered conductive and as a consequence tube 24 is rendered non-conductive. Curve 80, therefore, represents the current through tube 24 and shows the conducting period of tube 24 corresponding to the interval when the synchronizing or framing impulse is received. Since the receiver is running slightly slow, however, tube 28 is not simultaneously rendered non-conductive, because the commutator contacts 44-46 are not opened until a short time interval after the termination of the synchronizing impulse. During this time interval, which represents the phase difference between the transmitter and the receiver, tube 28 continues to conduct until the commutator contacts open even though tube 24 is rendered non-conductive. During this time, the polarity across tube 46 is reversed, and condenser 54 must discharge through resistances 52 before tube 28 can be biased to cut-off. The time constants of the resistance 52 and condenser 54 are arranged to exceed the time occupied by one synchronizing or framing interval. Tube 28, therefore, draws current through condenser 62 to charge the condenser in a positive direction for the duration of the interval between the termination of the synchronizing or framing signal and the opening of the commutator contacts 44-46. The current through tube 28 is represented by the curve 81, while the positive charge on the condenser 62 is represented by the curve 82. This potential may then be used to control apparatus for bringing about the proper desired speed and phase relationship between the receiver and transmitter.

The charge condition that existed on condenser 62 just prior to the reception of the synchronizing impulse is very quickly discharged as soon as both tubes 24 and 28 are rendered simultaneously conducting upon the receipt of a synchronizing impulse. This is because the combined impedance of the tubes is quite low when they are in a conducting condition, and as a result condenser 62 is discharged. The effect on condenser 68 will be described later.

In regard to Figure 2 it will be observed that the time interval T_2 remains fixed and represents the instant that the commutator contacts 44-46 open. In representing out-of-phase or improper speed conditions of the receivers with respect to the transmitter the time interval during which the synchronizing signal is received is

shown as shifted with respect to time T_2 . The instant the commutator contacts open was chosen as the reference point for the curves shown in Figure 2, since they represent conditions occurring at the receiver and the relative time intervals can best be represented and visualized by choosing that instant as fixed. Actually, the synchronizing or framing impulses are generally transmitted at a definite fixed rate and the operation of the commutator contacts vary in time relation thereto in accordance with the instantaneous speed and phase conditions of the receiver. Also, the time intervals T_1 and T_3 are also shown fixed in Figure 2 for purposes of simplicity, but naturally the intervals T_1 and T_3 vary relative to the received synchronizing impulses with variations in T_2 and, furthermore, the time interval between T_1 and T_3 (and likewise their spacing as represented in Figure 2) will actually increase or decrease slightly if the receiver is running slow or fast as compared to its proper operating speed.

Should the receiver be considerably out of phase and running considerably slow with respect to the transmitter, then the condenser 62 will be charged to its maximum or full positive potential. Such a condition is represented in Figure 2 where the curve 83 represents the received synchronizing signal and its time displacement with respect to the interval T_2 . It will be noticed that the displacement in this instance is considerably greater than the time displacement represented by the curve 79. Under such a condition of operation both tubes will be simultaneously rendered conducting, as explained above, and tube 24 will be rendered non-conducting simultaneously with the termination of the scanning or framing signal as represented by the curve 84. Tube 28, however, will continue to conduct as shown by the solid line curve 85 until the commutator contacts open at interval T_2 during which time the charge on the condenser 62 reaches a maximum. The charge on the condenser is represented by dotted curve 86.

If, however, the receiver or recorder is operating fast with respect to the transmitter, then a different operation of the bridge circuit takes place. The curve shown at 87 represents, for example, a slight advancement of the recorder with respect to the transmitter. Under such condition both tubes 24 and 28 will be simultaneously rendered conducting; however, the conductive condition of tube 28 will be terminated while the synchronizing impulse is still being received by reason of the operation of the commutator contacts 44-46. The curve 88 shows, therefore, the time interval during which the tube 28 will be permitted to pass current, which interval is less than the interval occupied by the synchronizing signal. Tube 24, however, will continue to conduct until the scanning synchronizing or framing signal has terminated. Curve 89, therefore, shows a curve representing the current through tube 24. Since tube 28 is rendered non-conducting by the operation of the commutator, prior to the discontinuance of operation of tube 24, a charge will be placed on condenser 62 in a negative direction, as indicated by the curve 90. It will be noticed that this charge is negative under a condition when the receiver is operating fast with respect to the transmitter, whereas in the above assumed example where the receiver was operating slower than the transmitter a positive charge was produced on the condenser.

If the receiver is appreciably faster and considerably more out of phase with respect to the transmitter then a still different set of circumstances exist. Under these conditions it will be assumed that the commutator contacts 44-46 open prior to the reception of the synchronizing impulse, as shown by curve 91. Under this condition tube 26 is not rendered conducting, but instead only tube 24 is rendered conducting and its conducting condition exists during the time of reception of the synchronizing signal. The period of conductivity of the tube 24 is represented by the curve 92. Under such a condition a stronger negative charge will be placed on condenser 62, as represented by the curve 93.

It will be seen, therefore, that a potential may be derived from the terminals 70-72 having a polarity depending upon whether the receiver is slow or fast with respect to the transmitter. Furthermore, it may be seen that the intensity of the potential or its magnitude is a function of the out-of-phase relationship between the receiver and the transmitter.

The polarity of the produced control potential will be in accordance with the nearest framing condition. Framing, therefore, will take place in the direction requiring the least amount of time, since the bridge circuit can produce either positive or negative control voltages. For example, should the receiver for some reason begin to run fast and finally reach a phase condition so that it is more than 180 degrees fast with respect to the transmitter, the then produced control potential will not operate to slow down the receiver but will instead continue to increase the speed of the receiver until the proper phase operating condition is reached, since it would require a lesser amount of time to frame the receiver in that direction than in the opposite. This is a distinct advantage over the prior art synchronizing systems where framing is always in the slow direction. As a result of the advantage the framing operation can be quite rapid.

It will also be noticed that there is no dead spot even with the scanner drum exactly 180 degrees out of phase with respect to the transmitter. Such a condition is represented by the curve shown at the bottom of Figure 2 wherein curve 94 shows the received synchronizing signals occurring at time intervals T_1 and T_3 and approximately 180 degrees out of phase with respect to the transmitter. As long as the receiver synchronizing signal overlaps to any extent the interval during which the commutator contacts 44-46 are closed, then the receiver or recorder will frame in the fast direction. However, if there is no overlapping the framing will be in the slow direction. Curve 94 shows a slight overlapping of the received synchronizing signal with the interval during which the commutator contacts are closed and under this condition tube 24 will be first rendered conductive as represented by the curve 95, while tube 26 remains non-conductive. During this slight time interval a negative charge will begin to develop on condenser 62, but as soon as the commutator contacts close (during which time the synchronizing signal is still being received, as indicated by curve 94), tube 26 will also be rendered conductive, and as long as both tubes are conducting no further charge will be deposited on the condenser but instead condenser 62 will be discharged. As soon as the synchronizing signal terminates, however, tube 24 will be rendered non-conductive, as indicated by curve 96, while

tube 26 will remain conducting, as indicated by curve 96 to thereby place a positive charge on the condenser 62, as indicated by the curve 97.

With the system so far described and without the inclusion of the condenser 66 and resistance 64, first order correction potentials will be produced across condenser 62. The additional feature of the system, however, includes the network of the resistance 64 and condenser 66 which are placed across the condenser 62. These elements permit second order correction to be obtained. As explained above the addition of the second order correction adds greatly to the accuracy of synchronization. The operation of the second order correction network is as follows:

It will be assumed that the value of the resistance 64 is of such value that condensers 62 and 66 will equalize to a fixed voltage in a time interval less than that represented by T_1 and T_3 . Then if the value of the condensers 62 and 64 are equal, the voltage available at the output terminals 70-72 will be divided according to the position of the movable contact 68 along with the potentiometer resistance 64. If the movable contact is at or near the center of the resistance 64 the result then is to obtain at the output terminals a potential equivalent to one-half the potential initially deposited on condenser 62 by the first framing impulse. Since condenser 62 is electrically isolated as soon as the synchronizing signal terminates, the charge on condenser 62 equalizes so that condensers 66 and 62 finally assume a charge equal to one-half the total charge or original charge on 62 (assuming condenser 66 had no initial charge). During this equalizing interval the voltage available at the output terminals 70-72 remains constant by reason of the inclusion of the potentiometer 64 and the position of the contact 68 at the center thereof. The next framing impulse recharges condenser 62 to some new value, and the output potential will then be the average of the charges then existing on condensers 62 and 66. This charge condition will then equalize to a new value during the following line interval. Accordingly, each time a signal framing impulse changes the charge on condenser 62 up or down the previous charge on condenser 66 is also slightly altered and is also effective toward controlling the potential available at the output terminals.

If for example, $2E_1$ represents the first charge on condenser 62, $2E_2$ the second charge, and so forth, then:

$$\text{1st order correction} = \frac{2E_1}{2} = E_1$$

$$\text{2nd order correction} = \frac{2E_2 + E_1}{2} = E_2 + \frac{E_1}{2}$$

$$\text{3rd order correction} = \frac{2E_3 + E_2 + E_1}{2} = E_3 + \frac{E_2}{2} + \frac{E_1}{4}$$

Inasmuch as the smaller fraction values of E_1 are not of greater magnitude corrections beyond the second order are not ordinarily necessary.

If condenser 66 is made unequal in value to condenser 62 or if the adjustable contact 68 is varied with respect to the resistance 64 the one-half factor above can be made any value between 1 and zero and the series added correctly to give the proper control. Normally the one-half factor has proven quite satisfactory.

Through the use of the resistances 64 and condenser 66 it may, therefore, be seen that by providing second order control a decided im-

provement is made in synchronizing facsimile receivers with transmitters.

The potential curves shown in Figure 2 indicating the charge on condenser 62 will now be referred to. It will be noticed that the curves 82 and 90 representing the potentials developed on condenser 62 when the recorder is operating only slightly slow and fast, respectively, show a charge of a predetermined value at the end of the charging period. This charge then reduces to a lesser value, as shown in the curves, due to the equalization of the charge between condensers 62 and 66 (for second order storage). In curves 86 and 98 there is no reduction in charge following the charging period since the charging period is of sufficient duration to permit both condensers 62 and 66 to reach maximum charge condition. Full correction potential is, therefore, available at terminals 70-72 when the receiver is appreciably slow or fast.

The produced potential available at terminals 70-72 may be conveniently used for controlling the speed or phase of operation of the facsimile receiver printer drum and various circuits or elements may be used that are responsive to this potential for bringing about the desired result. If, for example, the recorder is driven by a synchronous motor the potential as well as its polarity may be used to control the frequency of the supply voltage to thereby cause the receiver to increase or retard its speed to bring about the desired phase relationship. If, on the other hand, the receiver is driven by an induction motor the regulation of the receiver may still be accomplished by controlling the frequency applied to the motor or if this is not done the speed may also be altered by increasing or decreasing the voltage applied to the induction motor to thereby increase or decrease the speed of the motor. If the facsimile receiver drum is driven by an A. C. and/or D. C. series commutating motor or by a direct current shunt motor, the speed of the motor may be regulated by varying the voltage applied to the motor, by varying the field strength of the direct current shunt motor, or by regulating a braking action on the motor regardless of type. Since the control potential produced by the present invention and available at 70-72 may have one polarity or another, and since it varies in intensity, such a potential may be used for controlling the driving medium for the facsimile receiver irrespective of what medium is used.

Inasmuch as the present invention is concerned with the production of speed regulation control potentials, the facsimile receiver proper has not been shown, since it will be appreciated by those skilled in the art that any desirable facsimile receiver may be used.

It is to be understood that the use of the terms "pictures" or "picture signals" is meant to include the transmission of views, printed matter, checks, finger prints, photographs, weather and military or other type maps, financial statements, newspaper articles, advertisements, fashion plates, magazine articles, moving pictures, and the like, and, in fact, all types of subjects wherein a visual representation of the subject matter transmitted is to be reproduced at a receiving point.

Various alterations and modifications may be made in the present invention without departing from the spirit and scope thereof, and it is desired that any and all such modifications be considered within the purview of the present invention, except as limited by the hereinafter appended claims.

I claim:

1. A facsimile receiving system for receiving picture and synchronizing impulses, the picture signals being representative of a subject matter scanned at a transmitter and the synchronizing impulses occurring at regularly spaced intervals, comprising means responsive to the received synchronizing impulses to produce corresponding negative control impulses, a bridge arrangement including a pair of series-connected electron discharge paths, means responsive to the produced negative control impulses for varying the conductivity of one of the discharge paths between the limits of zero and a finite value, a facsimile receiver printer drum, switching means associated with said drum to intermittently apply an operating potential to the other of said paths to condition said path for conduction, means responsive to the produced negative control impulses to render said other path conducting when an operating potential is applied thereto by said switching means, means for maintaining conductivity to said other path irrespective of the continued conductive condition of said one path and irrespective of the continued presence of the negative control impulse until said switching means removes the operating potential, and a condenser associated with said discharge paths and connected between the junction of said discharge paths and a point of fixed potential in said bridge arrangement whereby a charge potential will be deposited on said condenser in a polarity determined by the direction of phase displacement between the operation of the switching means and the received synchronizing impulses, the intensity of the charge potential being a function of the degree of phase displacement.

2. A facsimile receiving system such as defined in claim 1 wherein said condenser has connected in parallel therewith the series combination of a resistance and a second condenser whereby a portion of the charge produced on said first condenser when an out-of-phase relationship exists will be transferred to said second condenser and retain thereby through said next succeeding charging interval, and output terminals connected to the common electrode of said condensers and to a point along said resistance whereby a correction potential may be derived from said terminals.

3. A facsimile receiving system for receiving picture and framing impulses, the picture signals being representative of a subject matter scanned and the framing impulses occurring at regularly spaced intervals, comprising means responsive to the received framing impulses to produce corresponding control impulses, a bridge arrangement including a pair of series-connected electron discharge paths, means responsive to the produced control impulses for varying the conductivity of one of the discharge paths between predetermined substantially fixed limits, a facsimile receiver printer drum, commutator means associated with said printer drum to intermittently apply an operating potential to the other of said paths to condition said path for conduction, means responsive to the produced control impulses to render said other path conducting when an operating potential is applied thereto by said commutator means, means for maintaining conductivity of said other path irrespective of the continued presence of the control impulse until said commutator means removes the operating potential, and an electron storage device connected between the junction of said series con-

nected discharge paths and a point of fixed potential in said bridge arrangement whereby a charge will be produced on said electron storage device having a polarity determined by the time sequence between the received framing impulses and the operation of the commutator means, the magnitude of the produced charge being a function of the degree of time difference.

4. A facsimile receiving system for receiving picture and synchronizing impulses, the picture signals representing a scanned subject matter and the synchronizing impulses related thereto occurring at regularly spaced intervals, comprising a bridge arrangement including a pair of series-connected electron discharge paths, means responsive to the received synchronizing impulses for controlling the conductivity of one of the discharge paths between predetermined limits, a facsimile receiver printer drum, means associated with said drum to intermittently apply an operating potential to the other of said paths to condition said path for conduction, means responsive to the received synchronizing impulses to render said other path conducting when said path is conditioned for conduction, means for maintaining established conductivity of said other path as long as an operating potential is applied thereto irrespective of the continued receipt of synchronizing impulses, and an electron storage device associated with said discharge paths whereby a charge potential will be placed on said electron storage device of an intensity and polarity determined by the relative conduction periods of the electron discharge paths.

5. A facsimile receiver for receiving picture and synchronizing impulses, the picture signals representing a subject matter scanned and the synchronizing impulses occurring at regularly spaced intervals, comprising means responsive to the received synchronizing impulses to produce corresponding negative control impulses, a facsimile receiver printer drum, switching means associated with said drum for opening and closing an electric circuit, a bridge arrangement including a pair of electron discharge tubes connected in series, a condenser in said bridge circuit associated with said tubes and connected between the junction of said tubes and a point of fixed potential, means responsive to the produced negative control impulses and to the operation of said switching means for causing said tubes to be simultaneously rendered conducting and non-conducting when the facsimile receiver is in proper phase and is operating in synchronism with received synchronizing impulses, and means to place a potential charge on said condenser when the facsimile receiver is out of phase and synchronism with the received synchronizing impulses, the polarity of the charge being determined in accordance with the direction of phase displacement and the intensity of the charge being determined in accordance with the degree of phase displacement and lack of synchronism.

6. A facsimile receiver for receiving picture and framing impulses, the picture signals representing a subject matter scanned and the framing impulses occurring at uniformly spaced intervals, comprising a facsimile receiver printer drum, commutator means associated with said drum, a bridge arrangement including a pair of electron discharge tubes connected in series, a condenser in said bridge circuit connected between the junction of said tubes and a point of fixed potential, means responsive to the received

framing impulses and to the operation of said commutator means for causing said tubes to be simultaneously rendered conducting and non-conducting when the facsimile receiver is in proper phase and is operating in synchronism with received framing impulses, and means to place a potential charge on said condenser when the facsimile receiver is out of phase with the received framing impulses, the polarity of the charge being determined in accordance with the direction of phase displacement and the magnitude of the charge being determined in accordance with the degree of phase displacement.

7. A facsimile receiver such as defined in claim 6 wherein said condenser is relieved of its charge each time a framing impulse is received, said condenser having connected in parallel therewith the series combination of a resistance and an electron storage element whereby a charge will be placed on said electron storage element from said condenser, the charge on said electron storage element being retained during framing impulse intervals, and output terminals connected to a point along said resistance and to the common electrode of said condenser and said electron storage element.

8. A facsimile receiver for receiving picture and framing impulses, the picture signals representing a subject matter scanned and the framing impulses occurring at regularly spaced intervals, comprising a facsimile receiver printer drum, commutator means associated with said printer drum, a circuit arrangement including a pair of series-connected electron discharge paths, an electron storage element in said circuit associated with said discharge paths, and means responsive to the received framing impulses and to the operation of said commutator means for causing said electron paths to be rendered conducting and non-conducting to place a potential charge on said electron storage element when the facsimile receiver is out of phase with the received framing impulses, the polarity of the charge being determined in accordance with the direction of phase displacement and the magnitude of the charge being determined in accordance with the degree of phase displacement.

9. A facsimile receiving system such as defined in claim 8 wherein said electron storage element has connected in parallel therewith the series combination of a resistance and a second electron storage element, and output terminals connected between the common terminals of the electron storage elements and a point along said resistance.

10. A facsimile receiving system for receiving picture and synchronizing impulses, the picture signals being representative of a subject matter scanned at a transmitter and the synchronizing impulses occurring at regularly spaced intervals, comprising a facsimile receiver printer drum, switching means associated with said drum and operating in synchronism and phase therewith, a condenser, and circuit means including a pair of electron discharge tubes responsive to the received synchronizing impulses and to the operation of said switching means for placing a potential charge on said condenser when a time interval exists between the termination of the received synchronizing impulses and the operation of said switching means, said circuit means operating to place a positive charge on said condenser when the synchronizing impulses terminate prior to the operation of said switching means and a negative charge on said condenser

when the synchronizing impulses continue to be received after operation of said switching means, the intensity of the charge being determined by the duration of the time interval.

11. A facsimile receiving system such as defined in claim 10 wherein said condenser has connected in parallel therewith the series combination of a resistance and a second condenser, and output terminals connected between the common element of the condensers and a point along said resistance.

12. A facsimile receiving system for receiving picture and synchronizing or framing impulses, the picture signals being representative of a subject matter scanned at a transmitter and the related framing impulses occurring at uniformly spaced intervals, comprising a facsimile receiver printer drum, commutating means associated with said printer drum and operating in synchronism and phase therewith, an electron storage element, and circuit means jointly responsive to the received framing impulses and to the operation of said commutating means for placing a potential charge on said electron storage element when an out-of-phase relationship exists between the termination of the framing impulses and the operation of said commutating means, said means operating to place a charge of one polarity on said electron storage element when the framing impulses conclude prior to the operation of said commutating means and a charge of opposite polarity on said electron storage element when the framing impulses continue to be received after operation of said commutating means, the magnitude of the charge being determined by the extent of the out-of-phase relationship.

13. A facsimile receiving system such as defined in claim 12 wherein said electron storage element has connected in parallel therewith the series combination of a resistance and a second electron storage element whereby a portion of the charge produced on said first electron storage element when an out-of-phase relationship exists will be transferred to said second electron storage element and retain thereby through said next succeeding charging interval point along said resistance whereby a correction potential may be derived from said terminals.

14. A facsimile receiving system for receiving picture and synchronizing or framing impulses, the picture signals being representative of a subject matter scanned at a transmitter and the related framing impulses occurring at regularly spaced intervals, comprising a facsimile receiver printer mechanism, circuit controlling means associated with said mechanism and operating in synchronism and phase therewith, an electron storage element, and means jointly responsive to the received framing impulses and to the operation of said circuit controlling means for placing a potential charge on said electron storage element when a time interval exists between the termination of the received framing impulse and the operation of said circuit controlling means, the polarity of the charge placed on said electron storage element being determined by the time sequence of the receipt of the framing impulse as compared with the operation of said circuit controlling means, the intensity of the charge being determined by the extent of the time interval.

15. A facsimile receiver such as defined in claim 14 wherein said electron storage element is relieved of its charge each time a framing impulse is received, said element having connected in parallel therewith the series combination of a

resistance and a second electron storage element the charge deposited on said second electron storage element from said first element being retained during receipt of framing impulses.

16. A facsimile receiving system for receiving picture and synchronizing or framing impulses, the picture signals being representative of a subject matter scanned at a transmitter and the related synchronizing impulses occurring at regularly spaced intervals, comprising a facsimile receiver printer drum, switching means associated with said drum and operating in synchronism and phase therewith, a condenser, and means responsive to the received synchronizing impulses and to the operation of said switching means for placing a charge on said condenser when a time interval exists between the termination of the received synchronizing impulses and the operation of said switching means, the polarity of the charge potential being determined by the time relationship of the termination of the synchronizing impulses as compared to the operation of the said switching means and the intensity of the charge being determined by the time differential.
17. A facsimile receiving system for receiving picture and synchronizing or framing impulses, the picture signals being representative of a subject matter scanned at a transmitter and the related framing impulses occurring at evenly spaced time intervals, comprising a facsimile receiver printer drum, commutator means associated with said drum and operating in synchronism and phase therewith, an electron storage element, and means jointly responsive to the received framing impulses and to the operation of said commutator means for placing a potential charge on said electron storage element when a time interval exists between the termination of the received framing impulses and the operation of said commutator means, the polarity of the charge being determined by the time relationship between the termination of the framing impulses and the operation of the said commutator means and the magnitude of the charge being determined by the time differential.

18. A facsimile receiver such as defined in claim 17 wherein said electron storage element is relieved of its charge each time a framing impulse is received, said electron storage element having connected in parallel therewith the series combination of a resistance and a second electron storage element whereby the latter element may be charged by said first element, the charge on said second electron storage element being retained during receipt of framing impulses, and output terminals connected to a point along said resistance and to the common terminal of said electron storage elements.

19. A facsimile receiving system for receiving picture and synchronizing or framing impulses, the picture signals being representative of a subject matter scanned at a transmitter and the related framing impulses occurring at regularly spaced intervals, comprising a facsimile receiver mechanism, circuit controlling means associated with said mechanism and operating in synchronism and phase therewith, an electron storage element, means responsive to both the received framing impulses and the operation of the circuit controlling means for placing a potential charge on said electron storage element when a time interval exists between the received framing impulses and the operation of said circuit controlling means, the polarity of the charge being determined by the time relationship of the received

framing impulses as compared with the operation of the said circuit controlling means and the magnitude of the charge being determined by the time differential, said electron storage element having connected in parallel therewith the series combination of a resistance and a second electron storage element, and output terminals connected between the common terminals of the electron storage elements and a point along said resistance.

20. A facsimile receiving system for receiving picture and synchronizing or framing impulses, the picture signals being representative of a subject matter scanned at a transmitter and the related framing impulses occurring at regularly spaced intervals, comprising a facsimile receiver mechanism, circuit controlling means associated with said mechanism and operating in synchronism and phase therewith, an electron storage element, means responsive to both the received fram-

ing impulses and the operation of the circuit controlling means for placing a potential charge on said electron storage element when a time interval exists between the received framing impulses and the operation of said circuit controlling means, the polarity of the charge being determined by the time relationship of the received framing impulses as compared with the operation of the said circuit controlling means and the magnitude of the charge being determined by the time differential, said electron storage element having connected in parallel therewith the series combination of a resistance and a second electron storage element whereby a portion of the charge produced on said first electron storage element when time interval exists will be transferred to said second electron storage element and retain thereby through said next succeeding framing impulse charging interval.

MAURICE ARTZT.
